UNITED STATES PATENT OFFICE.

JOHN A. HAIG, OF LADYMEAD, ASCOT, ENGLAND.

DESIGN FOR A BOTTLE OR FLASK.

45,295.

Specification for Design.

Patented Feb. 24, 1914.

Application filed January 20, 1913. Serial No. 743,209. Term of patent 14 years.

To all whom it may concern:

Be it known that I, JOHN A. HAIG, a subject of the King of Great Britain, residing at Ladymead, Ascot, Berkshire, England, have invented a new, original, and ornamental Design for Bottles or Flasks, of which the following is a specification, reference being had to the accompanying drawing, forming part thereof, and in which the figure is a perspective view of a bottle in accordance with my design, having on both sides an oval panel a, concave in cross-section, surrounded by a rim b and bearing a central circular depression c. Each edge of the bottle or flask is ornamented with an elongated oval panel d, slightly raised above the surrounding surface.

I claim—

The ornamental design for a bottle or flask, as shown and described.

JOHN A. HAIG.

Correction in Design Letters Patent
No. 46,295.

It is hereby certified that in Letters Patent No. 46,295, granted August 18, 1914, upon the application of Joseph Salomon and Harry Shaw, of Chicago, Illinois, for a Design for a "Mirror-Support," an error appears in the printed specification requiring correction as follows: Second column, after line 2, insert the words We claim; and that the said Letters Patent should be read with this correction therein that the same may conform to the record of the case in the Patent Office.

Signed and sealed this 29th day of September, A. D., 1914.

[SEAL.]

R. F. WHITEHEAD,

Acting Commissioner of Patents.
